UNITED STATES PATENT OFFICE.

THEODOR KOMMERELL AND EDWIN EDWARDS, OF MUNICH, BAVARIA,
GERMANY.

AUTOMATIC FLUSHING APPARATUS FOR CANALS, WATER-CLOSETS, &c.

SPECIFICATION forming part of Letters Patent No. 358,677, dated March 1, 1887.

Application filed June 12, 1886. Serial No. 204,952. (No model.) Patented in Germany March 10, 1886, No. 37,115; in France April 30, 1886, No. 175,845; in England May 14, 1886, No. 6,519, and in Austria-Hungary November 11, 1886.

To all whom it may concern:

Be it known that we, THEODOR KOMMERELL and EDWIN EDWARDS, both of Munich, Bavaria, Germany, have invented certain new and useful Improvements in Automatic Flushing Apparatus for Canals, Water-Closets, and Similar Objects, of which the following is a specification.

Patents for this invention have been granted 10 in Germany, No. 37,115, dated March 10, 1886; in England, No. 6,519, dated May 14, 1886, and in France, No. 175,845, dated April 30, 1886, and a patent has been applied for in Austria-Hungary on November 11, 1886.

15 This invention relates to an automatic flushing apparatus for canals, water-closets, and similar objects, which operates automatically and periodically, consuming a small quantity of water, which quantity can be adjusted to 20 varying requirements, forming an effective flushing apparatus for canals, closets, urinals, and the like, or the apparatus can be employed as an automatic and adjustable device for emptying reservoirs, vessels, and for similar uses.

25 Our improved apparatus will operate more effectively than any intermittently-acting flushing apparatus now employed, as it operates accurately with the very slightest (even drop by drop) supply of water, so that with a 30 consumption of, for instance, one hundred liters in twenty-four hours, at intervals of one, two, or more hours, according to the size of the reservoirs, while at the same time, as is the case with all known non-automatic flushing devices, water can be taken out of the reservoir at any time.

In the intermittently-operating flushing apparatus known up to this time the entire and automatic emptying of the reservoir—that 40 is, the object for which the apparatus is made—is always dependent on the quantity of the water-supply. As has been proved even with apparatus of the newest construction, the same require a water-supply of at least two cubic 45 meters in twenty-four hours if they are to operate accurately, and as this quantity of water can only be very exceptionally used for flushing closets, urinals, and the like, it renders their general introduction in most cases impossible.

The general adoption of our improved apparatus will be highly desirable in sanitary respects, for the reason that none but an apparatus with a very small consumption of water will render it possible to effect a regular daily 55 or repeated automatic flushing of the closets when apartments stand empty—for instance, during the vacations, or at any other time when the closets are left unused for any length of time—thus preventing the trap from becoming 60 dry and preventing the penetration of sewer or foul gases to the rooms. In order, however, to attain this object, which is of such eminent sanitary importance, at a slight cost, an apparatus had to be constructed which 65 would effect and deliver a powerful automatic flush with a small consumption of water, and this object, it is believed, is attained by the present apparatus.

To clearly explain the nature of the invention reference is made to the accompanying drawings, in which—

Figure 1 represents a vertical section, and Fig. 2 a top view or plan, of the improved apparatus.

75 The apparatus consists of a water tank or reservoir, A, provided with a trough-shaped reversing or oscillating lever a, which is so constructed that a metallic ball or rolling weight, b, can roll to and fro with the least possible friction. The fulcrum c of this lever a is arranged on the reservoir or tank, and the lever at one end is connected to a float, f, and the loose connecting-rod g of the flushing-valve h, by means of the joints or hinges d e.

85 The metallic or other ball b, on the one hand, and the correspondingly heavy flushing or outlet valve h, represent the two powers operating on the lever, while the float, in conjunction with the valve stem or rod, sets these powers 90 in action at suitable times. The length of the connecting-rod g is in proportion to the height of the water to be stored in the tank, said rod being provided at its lower end with a disk, which moves freely in the hollow space of the 95 valve, rising by the action of the float when the water rises in the tank until it comes nearly into contact with the cap i of the valve. At the same time the float will press the shorter arm of the lever gradually upward, and at the 100

moment when the latter is brought beyond the horizontal line the ball will roll to the opposite end of the lever, and thus lift the float, and also the valve, sufficiently to allow the water 5 to flow off at *k* without any obstruction.

If the water-line is so low that the float is not in contact with it, the weight of the float, in conjunction with that of the connecting-rod and valve, will overcome the weight of the ball, draw the shorter arm of the lever *a* down, and allow the ball to roll back to its original 10 position, thus firmly closing the valve.

In order that the outlet-valve be correctly guided when it is raised or lowered, three guide-rods, *l*, are provided. These are bent over at 15 their upper ends, so that the valve when raised will strike against them and be prevented from leaving them.

Should the quantity of water thus let off not 20 be sufficient, or a second flushing be considered desirable, the reservoir can be provided with a reserve chamber or space, *C*, and a siphon, *D*, in which case, as represented in the accompanying drawings, the inflowing water 25 is led into the said chamber and the partition-wall *p* arranged to be somewhat lower than the overflow height of the siphon. The water flows out of this reserve-chamber into the main chamber and sets the emptying mechanism in 30 operation, the water flowing off through the valve and main pipe *B*, and sucking the air out of the pipe leading to the reserve-chamber, thus producing a partial vacuum in the same, so that the siphon is put into action. This combination with the siphon is, however, not an 35 absolutely necessary feature of the invention, as by suitably constructing our improved apparatus any quantity of water can be brought to flow over automatically.

40 In cases where a flush is desired before the float can set the parts in operation automatically, it is only necessary to pull a cord or chain attached to the long arm of the trough-shaped lever *a*, as shown in dotted lines at *q*, when 45 the valve will be opened, and will close again as soon as the cord, chain, or its equivalent is released, so that a flushing of the closet or

other apparatus can be effected at any time, even after the automatic flush, for the reason that when the automatic flush operates the 50 tank is never emptied even when auxiliary compartments with a siphon are employed, as the siphon will only empty the auxiliary or reserve chamber. The intervals between the 55 automatic flushings or emptyings of the tank or reservoir are regulated by adjusting a cock, *m*, in the water-service.

If from any cause the automatic flushing device should not act, the water entering the tank would flow off through the siphon. It is evident that the various parts can be modified without departing from the tenor of our invention. 60

Having now particularly described and ascertained the nature of our said invention 65 and in what manner the same is to be performed, we declare that what we claim is—

1. A periodical flushing apparatus consisting of a tank, an outlet-valve, a shifting weight, connections between said weight and valve 70 whereby the shifting of the former shall unseat the latter, a float, and connections between said float and weight, whereby the rising of the float shall shift the weight, in substantially the manner specified. 75

2. A periodical flushing apparatus consisting of a tank, an outlet-valve, a tilting lever, a shifting weight applied to said lever and movable to either side of the fulcrum thereof, a float connected to said lever, and a loose connection between the lever and valve, whereby the lever may be moved by the rising of the float far enough to shift the weight before the valve will be unseated, substantially as set forth. 80

In witness whereof we have hereunto signed our names in the presence of two subscribing witnesses. 85

THEODOR KOMMERELL.
EDWIN EDWARDS.
